FLEXIBLE FISHING LURE

Donald L. Fitzpatrick, 12350 SW. 8th St.,
Miami, Fla. 33144

Filed Jan. 20, 1972, Ser. No. 219,612

Term of patent 14 years

Int. Cl. D22—05

U.S. Cl. D22—27

FIG. 1 is a side elevation of a flexible fishing lure, showing my new design.

FIG. 2 is a top plan view thereof.

FIG. 3 is a bottom plan view thereof.

FIG. 4 is a front elevation thereof.

FIG. 5 is a rear elevation thereof.

The broken lines are for illustrative purposes only.
I claim:

The ornamental design for a flexible fishing lure, as shown and described.
